S. SIMON

AUTOMOBILE WINDOW MECHANISM

Filed July 2, 1923

Patented Mar. 17, 1925.

1,530,426

UNITED STATES PATENT OFFICE.

SAMUEL SIMON, OF KANSAS CITY, MISSOURI.

AUTOMOBILE WINDOW MECHANISM.

Application filed July 2, 1923. Serial No. 649,032.

To all whom it may concern:

Be it known that I, SAMUEL SIMON, a citizen of the United States, residing at Kansas City, in the county of Jackson and State of Missouri, have invented certain new and useful Improvements in Automobile Window Mechanism; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to window sash hangers and window sash fastening means, being particularly applicable for use in connection with motor vehicles, and it is, therefore, illustrated as a part of a motor vehicle so constructed that the upper portion thereof constitutes a window frame in which are slidable sashes, yieldingly supported from a rail so that the window sashes may be readily moved longitudinally of the vehicle, the sashes being so constructed, however, that they may be jammed or forced into frictional contact with the lower rail of the frame so that they are held against sliding movement, whereby liability of noise from vibration will be eliminated. Prior to my invention, motor vehicles have been constructed with sliding windows or so called "curtains" which have longitudinal movement, but there have been objections to these because the frames warped, making it difficult to slide the curtains in some cases, and in still other cases there was too much play between the sashes and the frames which caused an unnecessary rattle or vibration in transit. There have been still further objections which are unnecessary to mention here. It suffices to say that according to my invention, the sashes can readily slide upon their supporting rails but can also be held rigid when it is so desired, so that the objectionable rattle will not be present.

The novel construction will be understood by reference to the following description, in connection with the accompanying drawings, in which:

Fig. 1 is a slightly elevational view of a motor vehicle to which my invention is applied, part of the top being broken away to show the relation of the suspending means and the locking means;

Fig. 2 is a fragmentary, perspective view of a window frame or sash, hung in accordance with my invention;

Fig. 3 is an end view of two sashes;

Fig. 4 is an end view of one sash, showing 60 the lock means in position;

Fig. 5 is an enlarged sectional view through one of the hangers; and

Fig. 6 is a detailed, perspective view of the lock. 65

Referring now to the drawings by numerals of reference:

1 designates a motor vehicle of appropriate construction, provided with what is commonly known as a "sliding sedan top," 2; that is, the top is constructed as a fixed part of the vehicle in contradistinction to the, so called, "one man top," which folds back. Along the upper portion of the normal body, 3, is the bottom rail, 4, of the window frame, and it is provided with rabbeted portions, having window strips, 5, therein, as will be well understood. The lower side edges of the top constitute the top rails of the window frame; for example, the one designated 6, Fig. 4, is provided with a grooved portion, 7, to the sides of which may be secured sash supporting rails, 8 and 9, each sash consisting of the usual rectangular frame 10, to the top rail, 11, of which are fastened the 70 hangers. Each hanger is shown as consisting of a plate, 12, having a lug, 13, to which is pivoted a bar, 14, on the free end of which is a roller or wheel, 15, offset with respect to the top rail, 11, and riding in one of the sash 75 supporting rails, 8 or 9. The bar, 14, is yieldingly secured to the top rail, 11, through the plate, 12, by a fixed pin, 16, carried by the plate, 12, and passing through the bar, 14, having at one end a head, 17, between which and the floor of the recess, 18, is an expansion spring, 19, coiled about the pin, 16, as will be clearly seen in Fig. 5. If a hanger plate, 12, is near each end of each sash, so that two wheels or discs, 15, will ride in one of the guide rails, 8 or 9, it will be apparent that the weight of the sash 80 will be carried by the spring 19. Therefore, the sash will be yieldingly supported by the hanger, and the construction is such that, 85

under normal conditions, the spring, 19, will be strong enough to maintain the lower rails of the sash slidingly above the window strips on the bottom rails of the window frames. Therefore, the window sashes may 90 readily slide longitudinally of the car. 95

When, however, it is desired to maintain the sashes in fixed position with respect to the frames, they may be locked through the medium of a cam, 20, pivoted in the flanges, 21 and 22, of a channel, 23, which is also fastened to the top rail, 11, of the sash, preferably about middle way between the ends of the sash. The cam, 20, can be actuated by a lever, 24, (see Fig. 6) so that the toe of it will bear against the dog, 20', pivoted in the flanges, 21 and 22. The dog has a roughened surface, which is adapted to engage the roughened surface of the strip, 120, in the groove, 7. At the same time, the sash will be forced downwardly until the lower rail comes into frictional contact with the window strip carried by the bottom rail of the frame. Then the sash will be locked against longitudinal movement. In the actual construction of a car, I may arrange a plurality of sashes on each side of the motor vehicle, as shown in Fig. 2. In Fig. 1, both sashes shown in Fig. 2 are slid back, leaving the front open. They can also both be slid forward, leaving the middle portion open, or they may both be moved slightly to uncover part of the middle and part of the front portion of the motor vehicle. In other words, the sashes may be arranged end to end, they may overlap each other partly, or they may overlap each other entirely. It will be apparent that in a construction similar to that herein described, the sashes would be easy to manipulate. They can be easily slid along their rails and readily fixed rigidly with respect to the rest of the motor vehicle, when it is desired to lock them against movement.

What I claim and desire to secure by Letters Patent is:

1. In combination with a motor vehicle having a window frame, a sash-supporting rail at the top of the window frame, a sliding sash, hangers carried by the top rail of the sash, each hanger comprising a pivoted bar having a free end normally urged toward the top rail of the window frame, and a roller carried by the free end of the bar, the roller being supported by the sash-supporting rail.

2. In combination with a motor vehicle having a window frame, a sash-supporting rail at the top of the window frame, a sliding sash, hangers carried by the top rail of the sash, each hanger comprising a pivoted bar having a free end normally urged toward the top rail of the window frame, a roller carried by the free end of the bar, the roller being supported by the sash-support-

ing rail, and means for locking the sash 60 against movement.

3. In combination with a motor vehicle having a window frame, a sash-supporting rail at the top of the window frame, a sliding sash, hangers carried by the top rail of the sash, each hanger comprising a pivoted bar having a free end normally urged toward the top rail of the window frame, a roller carried by the free end of the bar, the roller being supported by the sash-supporting rail, and means for forcing the lower rail of the window sash against the frame to hold it against sliding movement. 65 70

4. In combination, a window frame, a ⁷⁵
slidable sash in the window frame, a pivoted
lever carried by the top rail of the sash, a
roller on one end of the lever, a pin project-
ing from the top rail of the sash through the
lever, and an expansion spring carried by ⁸⁰
the pin and bearing against the lever to
force its free end normally down, and a rail
on which the roller rides.

5. In combination, a window frame, a slideable sash in the window frame, a pivoted lever carried by the top rail of the sash, a roller on one end of the lever, a pin projecting from the top rail of the sash through the lever, an expansion spring carried by the pin and bearing against the lever to force its free end normally down, a rail on which the roller rides, and a cam for forcing it down against the action of the spring to cause the lower end of the sash to engage the lower rail of the frame.

6. In combination with a motor vehicle having a window frame, a sash-supporting rail at the top of the window frame, a sash yieldingly supported by the rail and normally above the lower rail of the frame, a frictional strip on the bottom of the top member of the frame, a pivoted dog, having a roughened surface to engage the strip, and a pivoted cam for forcing the dog into frictional engagement with the strip.

7. In combination with a motor vehicle 10
having a window frame, a sash-supporting
rail at the top of the window frame, a sash
yieldingly supported by the rail and nor-
mally above the lower rail of the frame, a
frictional strip on the bottom of the top
member of the frame, a pivoted dog, having
a roughened surface to engage the strip, a
pivoted cam for forcing the dog into frictional
engagement with the strip, and for
forcing the lower rail of the sash into en-
gagement with the bottom of the frame. 11

In testimony whereof I affix my signature.
SAMUEL SIMON.
